(57) **CLAIM**

I claim the ornamental design for a fluid-injection device, as shown and described.

DESCRIPTION

FIG. 1 is a top, front, right perspective view of a fluid-injection device showing my new design;

FIG. 2 is a front elevational view thereof;

FIG. 3 is a rear elevational view thereof;

FIG. 4 is a left side view thereof, the right side being a mirror image of the left side view;

FIG. 5 is a top plan view thereof;

FIG. 6 is a bottom plan view thereof; and,

FIG. 7 is a bottom, front, right perspective view.

The evenly spaced broken lines depict portions of the fluid-injection device that form no part of the claim.

1 Claim, 7 Drawing Sheets
